[57] ABSTRACT

An electrical arrangement associated with the control and operating circuitry for an electrostatic printing machine of the type employing magnetic brush development for controlling the electrical bias on the developing magnetic brushes for enhancing print quality in situations wherein the background or density of an original to be copied is unsuitable for normal mode printing. Along with normal mode printing, there is provided means for biasing the magnetic brushes for originals having dark background or are of low density.

FIG. 2

CONTROLLING MULTIPLE VOLTAGE LEVELS FOR ELECTROSTATIC PRINTING

This invention relates to electrostatic printing machines, and in particular, to a control arrangement of voltage supplies for providing developing bias in accordance with the illumination characteristics of an original to be copied.

Electrostatic printing machines of the type employing an illumination system for illuminating an original generally are encumbered by an inability to present image rays for imaging purposes of sufficient depth or contrast as to produce properly an electrostatic latent image of usable condition for all possible input originals. For example, an original may have a dark or colored background and when exposed there results a latent image having charged and discharged areas both with high charge levels of very close values. When developed, the image will include intolerable amounts of background development. On the other hand, if the original is of the "low density" type, there usually results image areas almost completely washed out, so to speak. There have been attempts to offset these problems by varying illumination time. However, these attempts also adversely affect other areas of machine operation or the rate of production and therefore become inefficient.

Therefore, the principal object of the present invention is to improve electrostatic printing machines of the type employing magnetic brush development.

Another object of the present invention is to improve image quality obtainable from electrostatic printing for originals which in themselves have very poor irradiance characteristics.

The foregoing objects are attained by an arrangement of electrical circuitry and control devices which are adapted to be preset for originals which are classified as different for controlling energization of the development bias on the magnetic brushes utilized in the printing machine. This control of energization is in the form of connecting the brushes to voltage sources of different voltage levels thereby producing an electric field between the brushes and an electrostatic latent image in accordance with the need for the particular level so supplied. The control arrangement may also be associated with other processing devices in the printing machines in order to control their operation in the enhancement of print quality.

Further objects and advantages will become apparent after reading the following specification in conjunction with the accompanying drawings wherein:

FIG. 1 is a schematic sectional view of an electrostatic reproduction machine embodying the principles of the invention; and

FIG. 2 is a schematic representation of a control arrangement associated with some of the processing devices in the machine.

For a general understanding of the illustrated copier/reproduction machine, in which the invention may be incorporated, reference is had to FIG. 1 in which the various system components for the machine are schematically illustrated. As in all electrostatic systems such as a xerographic machine of the type illustrated, a light image of a document to be reproduced is projected onto the sensitized surface of a xerographic plate to form an electrostatic latent image thereon. Thereafter, the latent image is developed with

an oppositely charged developing material to form a xerographic powder image, corresponding to the latent image on the plate surface. The powder image is then electrostatically transferred to a support surface to which it may be fused by a fusing device whereby the powder image is caused permanently to adhere to the support surface.

In the illustrated machine, an original D to be copied is placed upon a transparent support platen P fixedly arranged in an illumination assembly generally indicated by the reference numeral 10, arranged at the left end of the machine. While upon the platen, an illumination system flashes light rays upon the original thereby producing image rays corresponding to the information areas on the original. The image rays are projected by means of an optical system for exposing the photosensitive surface of xerographic plate in the form of a flexible photoconductive belt 12 arranged on a belt assembly generally indicated by the reference numeral 14.

The photoconductive belt assembly 14 is slidably mounted upon two support shafts one of which is secured to the frame of the machine and is adapted to drive the belt 12 in the direction of the arrow at a constant rate. During this movement of the belt, the reflected light image of the original D on the platen is flashed upon the photoreceptor surface of the belt to produce electrostatic latent images thereon at an exposure station A.

As the belt surface continues its movement, the electrostatic image passes through a developing station B in which there is positioned a developer assembly generally indicated by the reference numeral 15, and which provides development of the electrostatic image by means of multiple magnetic brushes as the same moves through the development zone.

The developed electrostatic image is transported by the belt to a transfer station C whereat a sheet of copy paper is moved between a transfer roller and the belt at a speed in synchronism with the moving belt in order to accomplish transfer of the developed image solely by an electrical bias on the transfer roller. There is provided at this station a sheet transport mechanism generally indicated at 16 adapted to transport sheets of paper from a paper handling mechanism generally indicated by the reference numeral 17 to the developed image on the belt at the station C.

After the sheet is stripped from the belt 12, it is conveyed into a fuser assembly generally indicated by the reference numeral 18 wherein the developed and transferred xerographic powder image on the sheet material is permanently affixed thereto. After fusing, the finished copy is discharged from the apparatus at a suitable point for collection externally of the apparatus.

The belt 12 comprises a photoconductive layer of selenium which is the light receiving surface and imaging medium for the apparatus, on a conductive backing. The belt is journaled for continuous movement upon three rollers 20, 21 and 22 located with parallel axes at approximately the apex of a triangle. During exposure of the belt 12, the portion thereof being exposed is that part of the belt run between the roller 20 and the lower roller 21. The upper roller 22 is rotatably supported on a hollow shaft 23 which is rotatably driven by a suitable motor and drive (not shown) mounted in the machine. Further details regarding the structure of the belt assembly 14 and its relationship with the machine and

support therefor may be found in the copending application Ser. No. 102,312 assigned to the same assignee.

As shown in FIG. 1, the electrostatic printing machine employs magnetic brush development, utilizing a plurality of magnetic brushes 25, which span across the development zone B. The brushes are mounted for rotation on shafts 26 each of which is electrically connected to a bus bar 27 by suitable conductive brush elements 28. As is known in electrostatic development using magnetic brushes, it is desirable, for development quality and completeness, that a magnetic brush have associated therewith an electric field between it and a latent image being developed. The combination of magnetic flux lines and electric field lines enhances development, provides for solid area coverage and permits control of the uniform application of toner particles to image areas and the minimization of toner deposition in background areas.

The illustrated electrostatic machine also includes a pre-transfer corona generating device or corotron 30 which, when energized with an a.c. potential at a predetermined level, serves to modify to some degree, d.c. toner charges on the photoreceptor surface of the belt 12 after development and before the transfer of the developed image on the belt 12 to a sheet of paper at the transfer station C. This application of an a.c. current reduces the level of the potential of the image area so that the potential of the transfer voltage necessary to effect the transfer of toner particles from the developed image areas to the paper may be lessened. In turn, this lessening of the transfer voltage lessens the electrostatic forces holding the sheet upon the biased transfer roller 31 making strip-off of the sheet an easier operation. For those machines which utilize a corotron for transfer purposes, the pretransfer corotron lessens the electrostatic force variability between the sheet and the photoreceptor surface thus making strip-off more reliable for a wide range of images.

In FIG. 2 there is shown a control system incorporating electrical circuitry associated with the machine described above. The bus bar 27 is electrically connected to a terminal 32, which in turn is connected to an electrical power supply generally indicated in FIG. 1 by the numeral 33. Specifically, the bus bar is connected to a voltage source 34 as shown in FIG. 2 which is incorporated in the power supply 33 suitably connected to line voltage for the machine. This circuit including the source 34 is indicative of one provided on electrostatic machines employing magnetic brushes for development purposes. This circuit supplies development bias to the terminal 32 and to each of the magnetic brushes for the general all around use of the machine. Incorporated into this basic circuit in order to provide for development of originals which are either too dark in overall format or of low density, both conditions being beyond the capabilities of normal electrostatic reproduction, are various control devices for aiding in the reproduction of the originals so conditioned.

As shown in FIG. 2, the general power supply also includes two additional voltage sources 35, 36 which are adapted to be connected to the terminal 32. The electrical connection of either of the sources 34, 35 or 36 to the terminal and consequently, the bus bar 27, is selective. As previously indicated, the normal arrangement for general all around use of the machine, the source 34 is utilized and is connected to the bus bar by

way of two normally closed relay switch contacts 1K2 and 2K1. Therefore, in the normal mode of machine operation, when the machine is in "print" condition, the magnetic brushes 25 are energized with a developing bias supplied by the voltage source 34. For illustration purposes, it will be assumed the bias in normal mode operation is 200 volts.

The voltage source 35 is electrically connected to the bus bar by closing the normally open relay switch contact 1K1 and the normally closed relay contact 2K1 and the source 36 is electrically connected to the bus bar by way of the normally open relay switch contact 2K2. Actuation of the contacts 1K2 and 2K1 to open positions and the switches 1K1 and 2K2 to closed positions is obtained by means of the two relays 1K and 2K electrically connected for energization thereof by the machine logic 40 and a suitable voltage supply 41 therefor. Associated with the relay 1K for controlling energization thereof is a manually actuatable switch 42 suitably mounted on the control panel for the machine. Similarly, the relay 2K is adapted to be energized upon manual actuation of another switch 43 also suitably mounted on the control panel.

In operation, it will be assumed that an original has a dark background such as one in heavy color. In this situation, it is preferable that the developing bias on the magnetic brushes be higher than normal since the overall charge on the image areas resulting after exposure of this type of original is higher than normal. This is the result of the lessening of the dissipation of charge during the exposure step of machine processing since the dark background, like the image areas did not allow sufficient illuminating light rays to reach the photoreceptor belt 12 to dissipate the previously applied uniform charge in image configuration. With this type of original the machine operator before commencing actual printing, actuates the switch 42, labeled the "High Density" switch, for energizing the relay 1K. This energization actuates the contact 1K1 to a closed condition and the contact 1K2 to an open position. This results in the normal mode voltage source 34 being disconnected from the bus bar and the high voltage source 35 to be connected thereto. For illustration purposes, it will be assumed that the source 35 is adapted to supply 400 volts to the bus bar. In utilizing the parameters 200 volts for the source 34 and 400 volts for the source 35 that for dark background originals, a development bias of approximately twice the amount as normally used can be applied.

Assuming the original is characterized in having low density, it is preferred the development bias be less than normal since the image contrast level remaining on the photoreceptor belt after exposure is lower than adequate for normal development. For achieving acceptable copies from this type of original, the machine operator, before commencing the printing, will actuate the switch 43, labeled "Low Density" switch, for connecting the relay 2K to the voltage source 41 thereby energizing this relay. This energization causes the opening of the contact 2K1 for disconnecting the magnetic brushes from either of the two voltage sources 34, 35 and the closing of the contact 2K2 for connecting the low voltage source 36 directly to the brushes. This causes the development system to be more sensitive to low contrast images. For illustration purposes, in relation to the other assigned voltage values, the voltage

supplied by the source 36 may be in the neighborhood of 100 volts.

So that only one voltage source at a time can be utilized, the switches 42, 43 may be arranged so that actuation of one to a closed condition, opens the other and when the machine is in normal mode operation, both switches 42, 43 assume a non-actuated state.

To enhance development of an electrostatic latent image of an original of the low density type, the low density control relay 2K is also adapted to actuate a normally closed relay switch contact 2K3 to an open position for effecting the deenergization of the pre-transfer corotron 30. As shown in FIG. 2, the corotron 30 is connected to an a.c. oscillator 45 to be energized thereby producing a.c. corona upon the photoreceptor belt before a developed image is moved into the transfer position C. As previously stated, the pre-transfer corotron is utilized to neutralize or reduce the charge on the image and background areas in order to lessen the variations due to images necessary for effecting the transfer of a developed image to a sheet of paper at the transfer station. When the image and background potentials are nearly equal, as is the case with low contrast originals, the neutralizing effects of the pre-transfer corotron may further reduce or even eliminate the contrast characteristics of the image as presented to the transfer station. To preclude this from occurring, the low contrast images that have been enhanced by the low development bias are preserved for transfer by turning off the pre-transfer corotron. For the parameters chosen by way of illustration, better results have been obtained with the pre-transfer corotron deenergized when the low density switch 43 is actuated.

From the foregoing it will be appreciated that the invention contemplates the selective use of three voltage potentials for development control, depending upon the mode of machine operation; that is, in the normal mode, for the reproduction of originals of dark or colored background, or for the reproduction of originals of low density information. Coupled with the latter mode is the choice of utilizing the control of pretransfer conditions. This selective use enables the reproduction of originals not otherwise available in printing machines which operate in the conventional normal mode.

What is claimed is:

1. An electrostatic printing machine having a photoconductive member movable relative to a developing

zone, a magnetic brush developing device for developing electrostatic latent images on the member and normal mode circuit means for establishing an electric field of predetermined electrical potential between the magnetic brush device and the latent image during development of the same comprising

a first circuit including a voltage source of a potential higher than said predetermined potential, a second circuit including a voltage source of a potential lower than said predetermined potential, and control means associated with said circuits for selectively connecting one of said circuits or said normal mode circuit means to the magnetic brush device thereby impressing one of three potentials between the magnetic brush device and the latent image.

2. The machine in claim 1 wherein the normal mode circuit means includes a normally closed switch for normally supplying the magnetic brush device with electrical potential.

3. The machine in claim 2 wherein said first circuit includes a normally open switch between the voltage source associated therewith and the magnetic brush device and also includes means for opening said normally closed switch and for closing said normally open switch thereby effectively opening the circuit of the normal mode circuit means and closing said first circuit.

4. An electrostatic printing machine having a photoconductive member movable relative to a developing zone, means for uniformly charging the member, a magnetic brush developing device for developing electrostatic latent images on the member, means for transferring a developed image from the member to the support material, and an electrical energizing device adapted to neutralize some of the charges on the developed image prior to transfer thereof comprising, means for establishing a first electric field between the magnetic brush device and a latent image during development thereof, means for disrupting said first electric field and establishing a second electric field in its place and for rendering ineffective the neutralization action of the electrical energizing device.
